UNITED STATES PATENT OFFICE.

VICTOR M. SUMMA, OF ST. LOUIS, MISSOURI, ASSIGNEE TO AMERICAN CAR AND FOUNDRY COMPANY, OF ST. LOUIS, MISSOURI, A CORPORATION OF NEW JERSEY.

CAR-UNDERFRAME.

1,021,168.

Specification of Letters Patent. Patented Mar. 26, 1912.

Application filed March 31, 1910. Serial No. 552,508.

To all whom it may concern:

Be it known that I, VICTOR M. SUMMA, residing at St. Louis, Missouri, and being a citizen of the United States, have invented certain new and useful Improvements in Car-Underframes, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a plan view of an underframe embodying the features of the present invention, parts being broken away for the saving of space. Fig. 2 is a longitudinal section therethrough taken on the plane indicated by line 2—2 of Fig. 1. Fig. 3 is a transverse vertical section taken on the plane indicated by line 3—3 of Fig. 2, looking in the direction indicated by the arrows. Fig. 4 is a similar view taken on the plane indicated by line 4—4 of Fig. 2, looking in the direction indicated by the arrows. Fig. 5 is an end elevation. Fig. 6 is a detail section taken on the plane indicated by line 6—6 of Fig. 3, and looking in the direction of the arrow.

Referring to the details: A indicates the center sill, B, B the side sills connected to the center sills by the cross bearers C, C and bolster D, and also by the divided end sill E. The center sill A is constructed of a single I beam extending from end to end of the underframe and bifurcated at the ends for accommodating draft rigging as hereinafter specified, said beam being divided centrally as at 1, the two halves or sections 6 of the sill being connected by rivets passed through laterally extending and outstanding vertical flanges 2, 2 formed at the meeting ends of the sections. Said sections are also secured by top and bottom splice plates 4 and 5 riveted to the respective top and bottom flanges 50 of the beam. As each section 6 of the I beam comprising sill A is an exact duplicate of the other, and all of the parts connected to each is the same as the parts connected to the other, only one section has been illus-

trated in full and the description and showing are equally applicable to both. The outer end of the section 6 is bifurcated, terminating in outwardly extending arms forming the draft sills 7, 7, the web of sill A being formed integral and continuous with the vertical webs of the arms forming sills 7. The upper portion of the outer ends of said arms are connected by an integral web 8 which extends beyond and between the sections of end sill E, and is depressed as at 9 transversely for accommodating the end nailing strip, not illustrated. Web 8 extends outwardly to and is formed integral with a buffer or striking plate 8'. The upper portions of the outer ends of the vertical webs of each sill 7 terminate in laterally extending flanges 10 riveted to the respective inner end of the contiguous section of end sill E, the said inner ends of the section of the end sill being spaced by an outstanding portion of the connecting web 8. Sills 7 are formed integral with the usual drawbar stops 11, 11, and the lower portions of said arms extend outwardly beneath and to the outer edge of the connecting web 8, and are connected by a coupler carrier 12.

Each of the side sills B is preferably a beam of Z section, and is connected to the respective end sill E by corner bracket 13 and diagonal brace 14, the latter being connected to the horizontal web of the side sill and to a bracket 15 fixed to the end sill.

Bolster D comprises a pair of outstanding diaphragms 16, each formed of an I section and having lateral terminal flanges. A top cover plate 17 connects the diaphragms 16 and is riveted to the upper flanges thereof, said diaphragms having their lower flanges connected by outstanding enlargements 18 formed integral with the lower flanges of sill A. The vertical flanges of the inner terminals of the diaphragms 16 are connected together by rivets passed therethrough and through the intervening web of sill A. The said inner terminals of the diaphragms 16 have the lower portion of their outstanding vertical flanges rounded as at 19 for producing the king pin receiving opening therebetween which opening communicates with the usual center bearing 20 cast integral with and depending from lower flanges of sill A, the web of said sill being cut away within the area surrounded

by walls 19 for leaving the pin recess. Cast integral with and depending from the lower edge of each diaphragm 16 is the side bearing 21. Each of the diaphragms extends 5 outwardly beneath and is fixed to the web and depending flange of the respective side sill B.

At spaced points along the length of the sill A are arranged the cross bearers C, C, 10 each comprising upper and lower angle bar stress members 22 and 23 extending through sill A and connecting the side sills. Said sill, at the point of each cross bearer, is formed on opposite sides with outstanding 15 vertical flanges 24, and corner web flanges 25 extending between the web of the sill A and the flange 24. Each angle 22 is riveted to the upper web 25 and to the flange 24. Each angle 23 is riveted to the 20 lower web 25 and to flange 24, said flange 24 being formed with a thickened portion 24' disposing the vertical flange of angle 23 at one side of the planes of the vertical flange of angle 22 so as to accommodate an 25 interposed connecting strut 26 which is attached at its upper end to the vertical flange of angle 22 intermediate the length thereof, and at its lower end to the vertical flange of angle 23, said strut engaging the inner 30 face of the flange of angle 22 and the outer face of the flange of angle 23. The ends of angle 23 are riveted to the angle 22.

It will, of course, be obvious that many advantages are to be gained by the present 35 invention, among which may be named the very desirable advantage of rendering the center sill capable of being produced of cast steel without the expense and difficulty of handling a sill of the entire length of the 40 car, and at the same time, by the particular splicing thereof at the point specified, quite as efficient results are attained as if the sill were continuous and integral throughout. Obviously, as many openings 27 may be 45 left in the web of the beam comprising sill A as desired for reducing the weight of the structure and the saving of material.

What I claim is:

1. In a car underframe, the combination 50 of a center sill and a bolster connected thereto intermediate the length of the sill, said bolster comprising outstanding diaphragms fixed at their inner ends to the center sill and having curved flanges at their inner ends 55 forming a king pin recess, a portion of the center sill being cut away within the enclosure of said curved flanges.
2. In a car underframe, the combination 60 of a center sill and a bolster connected thereto, and comprising flanged diaphragms and a top cover plate connecting said diaphragms, means connecting the flanges of the diaphragms to the center sill, some of the flanges of the diaphragms being curved 65 for producing a king pin recess between the

diaphragms and a portion of the material of the center sill being cut away in the area inclosed by said curved flanges.

3. In a car underframe, the combination of an I beam center sill and a bolster connected thereto, intermediate the length thereof, and comprising outstanding diaphragms each having laterally extending flanges at its inner end, and a portion of each of said flanges being curved for producing a central king pin recess, and means connecting said flanges to the center sill, a portion of the material of the center sill being cut away within the area inclosed by the curved portions of the flanges. 70

4. In a car underframe, the combination of an I beam center sill, a center bearing integral therewith, and a built up bolster connected to the center sill above the center bearing. 75

5. In a car underframe, the combination of an I beam center sill and a built up bolster connected thereto, intermediate the length thereof, the lower flanges of the I beam being formed with outstanding enlargements 80 beneath and connected to the bolster. 90

6. In a car underframe, the combination of an I beam center sill, a built up bolster connected thereto, intermediate the length thereof, the lower flanges of the center sill 95 being formed with outstanding enlargements beneath and connected to the bolster, and a center bearing formed integral with and depending from said lower flanges with in the area of said enlargements. 100

7. In a car underframe, the combination of a cast I beam center sill having laterally extending flanges, intermediate the length of the sill, and between the upper and lower flanges of the beam, and a built up cross 105 bearer fixed to the said laterally extending flanges.

8. In a car underframe, the combination of a flanged beam center sill, built up cross bearers having their chords disposed in different vertical planes, flanges outstanding from the center sill for snugly receiving the chords, and means connecting said chords to said flanges. 110

9. In a car underframe, the combination of a flanged beam center sill, a vertical flange outstanding from each side thereof, a pair of horizontal webs connecting each of said vertical flanges to the main web of said sill, a portion of one face of each vertical flange being spaced from the vertical plane of the other portion of the same face of said flange, and a cross bearer comprising chords connected to said flanges and webs, one of the chords being connected thereto in a different vertical plane from the other. 115 120 125

10. A cast center sill comprising a flanged beam formed in two sections, and having their meeting ends provided with the upper and lower surfaces substantially continuous 130

- of the upper and lower surfaces of the main body portion of the sill, the meeting ends of the sections being formed with contacting vertical flanges, means directly connecting 5 the contacting flanges and upper and lower splice plates extending across the line of juncture of the sections and fixed to the upper and lower flanges thereof.
11. In a car underframe, the combination 10 of an I-beam center sill, and a built up bolster connected thereto intermediate the length thereof, the lower flanges of the center sill being formed with outstanding enlargements beneath and connected to the 15 bolster, and a center bearing formed integral with the center sill adjacent said enlargements.
12. In a car underframe, the combination 20 of a flanged center sill a built up bolster connected thereto, intermediate the length thereof, the flanges of the center sill being formed with outstanding enlargements connected to the bolster, and a center bearing formed integral with the center sill adjacent 25 said enlargements.
13. In a car underframe, the combination of a center sill having laterally extending horizontal flanges intermediate its length and between its upper and lower longitudinal margins, and a cross-bearer fixed to said flange and extending through said center sill. 30
14. In a car underframe, the combination of a center sill having flanges intermediate its length and between its upper and lower longitudinal margins, and a cross-bearer having both its chords fixed to said flanges. 35
15. A cast center sill comprising a flanged beam formed in two sections, the adjacent ends of the sections being formed with vertical flanges, means connecting the vertical flanges of one section to the vertical flanges of the other section, and a splice plate connecting other portions of said sections. 40
16. In an underframe, the combination of a flanged center sill and a bolster fixed thereto, the flanges of said center sill being formed with outstanding enlargements connected to the bolster and said bolster being extended through said center sill. 45

In witness whereof, I have hereunto set my hand in the presence of two witnesses.

VICTOR M. SUMMA.
